UNITED STATES PATENT OFFICE.

GEORGE REPLOGLE, OF LA FAYETTE, INDIANA.

LINEMAN'S CHAIR.

1,264,975.

Specification of Letters Patent.

Patented May 7, 1918.

Application filed October 30, 1917. Serial No. 199,389.

To all whom it may concern:

Be it known that I, GEORGE REPLOGLE, a citizen of the United States, residing at La Fayette, in the county of Tippecanoe and State of Indiana, have invented certain new and useful Improvements in Linemen's Chairs, of which the following is a specification:

This invention relates to cable inspecting devices attached to, and moving with, a lineman's chair or equivalent device, such as is ordinarily supported by, and runs upon, a supplemental supporting cable or wire, sometimes known as a messenger cable, the latter being arranged in proximity to a cable or conductor of a telegraph or telephone line or any other employer of electricity and supporting the same, in order that the occupant of the chair may conveniently inspect the said conductor and repair it if necessary.

Such a lineman's chair, as heretofore constructed, and without my novel appliance herein described, will permit the occupant of the chair to inspect the cable or other conductor from above with convenience, but he must bend inconveniently and more or less twist his body to obtain a view of the underside of the cable, so there is always some risk that defects not easily discernible from above may altogether escape notice; besides, the work is impeded and delayed and the inspecting lineman is made needlessly uncomfortable. If the chair were hung so low as to afford a good view of the underside of the conductor in a natural position of the lineman there would be even greater difficulty in obtaining a clear view of the upper part of the conductor. In short, it is not possible to hang the chair and its occupant so that all parts of the conductor or cable will be seen by him distinctly and at once from one point by direct view.

To do away with this disadvantage I employ also indirect or reflected vision, providing the chair with a mirror which will supply a reflected image of the parts of the cable or conductor not seen from above, while the direct vision of the lineman suffices for the upper parts of said conductor; consequently the lineman while retaining a single natural posture with his eyes at one point can see at a glance all of the wire, both above and below the center, which is for the time in proximity to the chair or seat and the mirror. By moving the chair

from point to point the entire conductor is brought at all points under inspection.

To this end my invention consists mainly in the combination of such a mirror with such a chair; also in certain additional features of adjustment and construction hereinafter more particularly set forth and claimed.

In the accompanying drawings: 65

Figure 1 represents a perspective view, slightly broken away, of a lineman's chair having a mirror attached thereto according to my invention and mounted on a chair-supporting messenger wire or cable in proximity to the cable or conductor which is to undergo inspection;

Fig. 2, an end elevation of the same on a smaller scale, looking from the right to the left, the conductor and chair supporting messenger wire or cable being shown in cross-section;

Fig. 3, a transverse section of the mirror, enlarged, taken in proximity to that one of its ends which is presented foremost in Fig. 2, and a part of one of the supporting arms of the chair being shown in elevation; and

Fig. 4 represents an enlarged detail view of the means for holding the mirror in different positions of inclination. 85

A designates the chair suspending or messenger wire, B the conductor or cable which is supported by said messenger and which is to be inspected, C the bent suspending arms of the lineman's chair, D the platform which constitutes the seat of the said chair, E a stout base bar, which extends longitudinally under and in contact with said platform or seat, and is supported adjustably by the lower ends of said arms, being 90 also clamped to said seat by a pair of metal clips or brackets F, which are bent to receive and fit the ends of said bar and are secured to said seat or platform by bolts G. The upper parts of the arms G are bent to supply 100 recesses receiving the grooved rollers H, which rest on the supporting messenger wire A and suspend the chair movably as usual, said rollers running along the supporting cable or messenger wire A as the chair is 105 pulled from point to point by the lineman. These rollers turn on ordinary spindles g, which may be in the form of bolt as shown, passing through the parallel upright bars of the bent upper parts of said arms. 110

From the bent upper part of each arm C an outwardly and downwardly curved mir-

rior-suspending part I extends as shown, being provided at its lower end with disk-form integral bifurcations or jaws J, provided with peripheral ridges or broad serrations 5 j adapted to engage similar ridges or segments k on the proximate face of integral terminal extensions K of bar 3 to which the frame 1 of mirror 2 is rigidly secured by any suitable means. These ridges k collectively 10 constitute at each end of the bar 3 a segmental rack adapted to mesh with the ridges j of the corresponding pair of bifurcations J in any one of divers positions of the tilting of the mirror 2 and said bar 15 3. A pivot bolt L passes through each pair of such bifurcations J and has an eye-bolt M hung thereon between each pair of bifurcations J. The lower end of said eye-bolt passes through the extension K of bar 3 20 proximate thereto and receives below the latter a nut N. The two nuts N are the clamping devices for holding the mirror 2 in any position of inclination to which it may be tilted around said disk-form bifurcations 25 J. To adjust the inclination of the mirror 2, these nuts N are loosened, the mirror is shifted on its longitudinal axis to the position of inclination desired and the nuts N are tightened again, drawing the ridges k 30 of the segments K into engagement with different ridges j from those previously engaged. By tightening said nuts the mirror is held securely in its adjusted position.

The mirror is of sufficient length to permit 35 a considerable extent of the conductor to be inspected both below as well as above without shifting the position of the chair, and reaches, as explained, nearly from one of the end arms C to the other. The end arms 40 C, the base bar E and brackets F with their bolts make up a strong frame for the chair and the arms C serve an additional purpose as mirror supports by reason of the downwardly extending parts I and the journaling construction above described.

Having thus described my invention, what I claim as new and desire to secure by Letters Patent is:

1. A suspending device for a cable inspector, adapted to be moved along in a line parallel and proximate to a cable or other conductor of electricity and provided with a mirror arranged to show the underside of the conductor to a person inspecting the upper side thereof.

2. In combination with a supporting means arranged parallel and proximate to a conductor and a device supported by and running along the said means and adapted 60 to carry a person, a mirror attached to said device and arranged to show the lower part of the conductor to one in said device who inspects the conductor from above.

3. In combination with a lineman's chair 65 and a supporting wire or cable from which

said chair is movably suspended in proximity to a conductor, a mirror carried by said chair and arranged to show the lower part of said conductor to an occupant of said chair while the upper part of said conductor is inspected by him from above.

4. In combination with a chair-supporting cable, a lineman's chair suspended therefrom by arms provided with rollers which run on said cable and a mirror carried by said arms and arranged to display the lower part of the conductor to be inspected.

5. A pivoted mirror arranged in proximity to a cable which is to be inspected, in combination with a lineman's chair and a supporting cable from which said chair is suspended and on which it is movable endwise of said cable, the said chair being provided with arms from which the said mirror is suspended for tilting, and with means for locking said mirror in any position to which it may be thus tilted.

6. A tiltable mirror for a lineman's chair, said mirror having attached longitudinally projecting parts serrated on their upper faces, in combination with suspending means having correspondingly serrated parts and means for clamping together said projecting parts and suspending parts, with their respective serrations in engagement, in any one of divers positions into which said mirror may be tilted.

7. A suspending frame for a lineman's chair, provided with disk-form ridged parts and pivots, in combination with eye-bolts hung from said pivots and a mirror having attached terminal parts which are perforated to receive said eye-bolts and provided with ridges on their upper faces for engagement with the ridges of said disk-form parts, in any one of divers positions of inclination of said mirror and said terminal parts.

8. A tiltable mirror, in combination with a lineman's chair and its suspending frame having downwardly presented disk-form bifurcations peripherally ridged, a bar attached to said mirror and having on its ends segmentally arranged ridges for engaging the ridges of said disk-form parts, pivot bolts extending through each pair of bifurcations and means for suspending said bar and mirror from said bolts, said means being adapted to be tightened for clamping said ridges into engagement into any position of tilting assumed by said mirror.

9. A suspending device for a cable inspector adapted to be moved along in proximity to a cable or conductor and provided with a tiltable mirror and means for locking said mirror in any one of several positions of inclination, said mirror serving to show the underside of the cable.

10. A suspending device for a cable in-

spector provided with serrated parts, in combination with a mirror having serrated parts attached thereto and adapted to engage the serrated parts first mentioned in any 5 one of several different positions of inclination of said mirror and means whereby said mirror may be clamped to said supporting device in any such position.

11. A suspending device for a cable in-
10 spector adapted to be moved along in prox-

imity to a cable or conductor and provided with an adjustable reflector and means for locking said reflector in any one of several positions of adjustment, said reflector serving to show a portion of the cable or con- 15 ductor.

GEORGE REPLOGLE.
